UNITED STATES PATENT OFFICE.

ANE PIETER SCHAT, OF Utrecht, NETHERLANDS.

AUTOMATIC DAVIT.

1,369,133.

Specification of Letters Patent Patented Feb. 22, 1921.

Application filed June 21, 1920. Serial No. 390,603.

To all whom it may concern:

Be it known that I, ANE PIETER SCHAT, a subject of the Queen of Holland, residing at Utrecht, Netherlands, have invented certain new and useful Improvements in Automatic Davits, of which the following is a specification.

This invention relates to automatic davits of the type in which the axes of rotation are inclined outwardly toward the ship's side so that they have a permanent tendency to swing automatically by gravity to their lowermost position over the water.

In order that davits of this type may swing outwardly automatically even from the high side of a ship with a heavy list, they should be disposed at a considerable angle outwardly, but this causes the boat with its davits, especially at the low side of the ship to move at a high speed and oscillate violently for some time. This oscillation could be avoided by the provision of mechanism adapted to stop the davits in their extreme outboard position, but it will be readily understood that the sudden stoppage of a heavy system moving at considerable speed would be likely to cause one or other part to break.

It has previously been proposed to control the swinging out of davits of the type referred to, by means of tackle connected to a bar which is pivotally connected to the davit heads, whereby the movements of both davits are made synchronous with one another.

The present invention consists in a pair of davits having their axes of rotation inclined outwardly toward the ship's side and adapted to rotate outboard by gravity in directions which are opposite to each other, and having means for controlling the rotary speed of the davits.

The invention further consists in a pair of davits in which brake members are adapted to engage the davits or elements rigidly secured thereto.

It is not necessary for the controlling means to engage the davits directly since they might engage a member flexibly coupled with the davits, for instance, the boat. It is preferred, however, to employ a brake member engaging the davit itself, or a part rigidly secured thereto, said member being adapted to exert a pressure on the davit or on a part immovably secured thereto, the

pressure being adjustable, for instance, by means of a screw and handwheel.

Referring now to the accompanying drawings which illustrate two embodiments of the invention,

60

Figure 1 is an elevation of an "automatic" davit 1 rotatably mounted in a frame 2 secured to the deck of a ship. As clearly shown, the axis of rotation of the davit is inclined at a considerable angle from the vertical outwardly. The means for controlling the rotation of the davit comprise a brake band 3 which is passed around the davit and the action of which may be regulated by means of a screw 4 provided with a hand wheel 5.

Fig. 2 is a sectional view on the line A—B in Fig. 1, and drawn to a somewhat larger scale. It will be understood that it is preferred to employ a brake collar or drum rigidly secured to the davit.

Fig. 3 is a vertical longitudinal section showing the upper portion of a frame 6 of an "automatic" davit 1, and,

Fig. 4 is a cross-sectional view on the line C—D in Fig. 3. The controlling means here comprise two brake shoes 7 and 8 in engagement with the davit and adapted to be forced against it with any desired pressure by means of a screw 9 provided with a hand wheel 10, cover plates 11 and 12 serving to prevent dust and water from interfering with the proper operation of the mechanism.

By suitable adjustment of the braking pressure the boat may be caused to swing out gradually and smoothly under all conditions, even when the axes of rotation of the davits, owing to an abnormal position of the ship, make a very great angle with the vertical. If desired the davits may be locked at any position in either their outward or inward movement and thus prevented from swinging back and forth, simply by increasing the braking pressure.

100 The davits are preferably used in conjunction with collapsible chocks such as are described in the specification of my co-pending patent application No. 388,528, but any suitable kind of chocks may be used.

105 It will be understood that the invention is not limited to davits for use on ships, but that it may also be embodied in davits mounted, for instance, on a pier, a wharf or other landing stage.
